GAME APPARATUS

Edward A. Herr, Philadelphia, Pa.

Application May 12, 1939, Serial No. 273,352

3 Claims. (Cl. 273—6)

This invention relates to game-boards and, more particularly, to game-boards utilized in games involving the projection and impact of spheres such as marbles or the like.

An important object of the invention is the provision of a playing surface for such game-boards having elastic properties such that bouncing of the spheres as a result of impact is substantially eliminated, thereby adapting small boards for use in playing marble games of various sorts. More specifically, it is the object of the invention to produce a playing surface which is elastically dead and gives substantially no rebound of a sphere even when forcibly impacted thereagainst.

Another object of the invention is the provision of a game-board for use in playing marble games simulating the games played upon the ordinary pool or billiard table.

These and other objects I attain by the construction shown in the accompanying drawing wherein,

Fig. 1 is a plan view of a game-board constructed in accordance with my invention, a portion of the playing surface being broken away to show the underlying supports therefor;

Fig. 2 is a section on line 2—2 of Fig. 1;

Fig. 3 is a section on line 3—3 of Fig. 1;

Fig. 4 is an enlarged perspective showing the mounting of one of the pockets; and

Fig. 5 is a detail sectional view on line 5—5 of Fig. 1 showing the arrangement of the playing surface adjacent the pockets.

Referring now more particularly to the drawing, the playing surface per se comprises a sheet 10 of unelastic material. Few substances are satisfactory for such sheets, but among these substances I have discovered that felt base floor coverings, such as disclosed in the patent to Frank B. Foster, No. 1,249,734, granted December 11, 1917, for "Rug and the process of making the same," and its counterparts linoleum and heavy roofing papers, give excellent results. Such materials, in addition to being elastically dead, are readily compressible and have the property of slowly resuming their original condition after impact.

This sheet is preferably covered with a fabric or other covering producing the desired playing surface as indicated at 11 and is supported in spaced relation to the underlying surface upon which it is arranged by means of unelastic battens, indicated at 12, between which air spaces 13 are formed. Battens 12 may be conveniently formed from felt or some similar substance.

The underlying surface may be either the surface of a table or other support upon which the playing surface is arranged, or I may provide a supporting backing sheet 14 of stiff cardboard, or some analogous substance.

The playing surface may be defined by an upstanding wall 15 and in the game-board at present illustrated and intended for use in playing games simulating those played upon a pool table, the wall 15 is made sectional, the spaces between the sections defining entrances 16 to pockets 17.

The pockets 17 may be conveniently formed by wire cages and are connected with the adjacent ends of the wall sections by very light springs 18 which are attached to the wall sections and have eyes 19 receiving angular tips 20 formed upon a member of the cage or pocket 17. The playing surface adjacent the pockets is preferably slightly elevated, as more clearly shown in

Fig. 5, an additional batten 21 being utilized to produce this elevation. By adopting this construction, any tendency of the spheres 22 to roll into the pocket by reason of some slight motion of the playing surface itself is eliminated. The

inner surface of the wall sections is preferably equipped with a cushioning material such as sponge rubber, indicated at 23.

I have found that a playing surface constructed in the manner above described has substantially no inherent elasticity and that balls will not fly from this surface due to impact against one another, or due to impact against the surface itself even though the impact is severe.

I have also found that by attaching the wire cages 17 to the playing surface through the light springs 18 the impact of the spheres against the wire cage is cushioned and the tendency to rebound is substantially eliminated and at least reduced to such a point that the shoulder 24 presented by the edge of the playing surface per se and of its supporting battens is sufficient to prevent return of the spheres to the playing surface. The board may, of course, be equipped with levelling devices such as adjustable screws

25, and may be, additionally, equipped with small levels 26 to indicate its position.

Since the construction illustrated is but one of many forms which the game-board may assume, and since the structure is otherwise capable of considerable modification, I do not wish to be understood as limiting myself to the structure herein shown except as hereinafter claimed.

I claim:

1. In a game board for use in games involving the projection and impact of spheres, a play-

ing surface composed of a top sheet of soft, compressible and elastically-dead material possessing the property of resuming its original condition slowly after impact; a rigid backing sheet for said top sheet; and soft and elastically-dead battens secured to said backing sheet and disposed between the top and backing sheets in spaced relation for supporting portions of said top sheet with portions of said top sheet between said spaced battens free from contact therewith, said top sheet and battens providing a playing surface from which the spheres will not bounce or rebound when impacted thereagainst.

2. In a game board for use in games involving the projection and impact of spheres, a playing surface composed of a top sheet, a rigid backing sheet for said top sheet, battens disposed between the top and backing sheets in spaced relation and supporting said top sheet, and an upstanding wall surrounding said playing surface and having an opening therein defining the mouth of a pocket at the edge of said playing surface, the ends of the battens adjacent said

pocket being of greater height than the remainder of the battens, whereby the playing surface adjacent said pocket is slightly elevated with respect to the remainder of said playing surface.

5 3. In a game board for use in games involving the projection and impact of spheres, a playing surface composed of a top sheet of soft, compressible and elastically-dead material possessing the property of resuming its original condition slowly after impact; soft and elastically-dead batten disposed beneath the sheet in spaced relation for supporting portions of said sheet with portions of said sheet between said spaced battens free from contact therewith; and an upstanding wall surrounding said playing surface and having an opening defining the mouth of a pocket at the edge of said playing surface, the ends of the batten adjacent said pocket being of greater height than the remainder of the battens, whereby the playing surface adjacent said pocket is slightly elevated with respect to the remainder of said playing surface.

EDWARD A. HERR.
